INVENTOR

Alfo Rapisardi

UNITED STATES PATENT OFFICE

ALFIO RAPISARDI, OF BOSTON, MASSACHUSETTS

PHONOGRAPH

Application filed May 7, 1926. Serial No. 107,361.

This invention relates to the reproducing apparatus of phonographs and is especially concerned with the construction of the stylus which is directly vibrated by the record.

5 It is the chief object of the invention to improve the construction of the stylus and adjacent parts of the reproducing mechanism of a phonograph with a view to improving the quality of the reproduction. The invention aims especially to eliminate the scratching or surface noise which practically always accompanies the playing of a phonograph record, and to make the reproduction true and accurate.

15 The nature of the invention will be readily understood from the following description when read in connection with the accompanying drawings, and the novel features will be particularly pointed out in the 20 appended claims.

In the drawings,

Figure 1 is a side view of a part of a reproducer showing it in its operative relationship to a record;

25 Fig. 1a is a view of a part of the reproducer shown in Fig. 1 but using a different form of stylus;

30 Figs. 2 to 5, inclusive, are cross-sectional views through the axes of several forms of styli constructed in accordance with this invention; and

Figs. 2a to 5a, inclusive, are views similar to Figs. 2 to 5, respectively, but each showing a one-piece or integral construction of stylus.

35 Referring first to Figs. 2 to 5, inclusive, four slightly different forms of stylus are shown, each comprising a needle holder or body and a needle supported therein. The holders or bodies of the several constructions 40 shown are indicated at 2, 3, 4 and 5, respectively. Each of these needle holders is of approximately globular shape, those shown in Figs. 3, 4 and 5 being somewhat elongated.

45 Each body or holder includes a shank 6, preferably integral with the body, and adapted to be secured in the socket of a phonograph reproducer of the ordinary commercial type. Formed in the side of each body opposite to the shank 6, and preferably co-axial therewith, is a socket to receive a phonograph 50

needle 7 like that shown in Fig. 6, the needle being releasably secured in the holder or body by a set screw 8.

55 It will be observed that the body or holder of each stylus is very large or massive when compared to the needle or the shank, and that its external surfaces are rounded and smooth and are devoid of any projecting angles. These holders may be made either of metal, bakelite, bone, hard rubber, or a great 60 variety of other materials. The needles 7 usually are made of steel, properly tempered, a spring temper being preferable. The needles may vary considerably in size, and it is convenient to use different sizes according to the results desired, a small needle of, say, ten to fifteen thousandths of an inch in diameter giving a softer tone than a larger needle of, say, twenty-five or thirty thousandths. In either case, however, the extremity or point which runs in the groove of the record should be made to fit the groove accurately. The dimensions of the bodies or 65 holders 2, 3, 4 and 5 may vary, but preferably should be between three thirty-seconds and one-quarter of an inch in diameter. I have obtained very satisfactory results with 70 bodies of about three-sixteenths of an inch in diameter.

75 A stylus of the construction shown in Figs. 2 to 5 equipped with a needle of the kind described produces unusually pleasing results. The scratching sound is practically eliminated, and the fine gradations in tone and quality are faithfully reproduced without the 80 usual tendency to emphasize certain tones or notes which is always an objectionable characteristic and is present in all prior forms of phonograph reproducers of which I am aware.

85 The reasons for the improved results are somewhat obscure, but a long series of experiments and extensive trials seem to indicate very clearly that the use of a relatively massive body of proper shape and located 90 near the point of the needle is an important factor in producing these results. The shape of this body is important; that is, its outer surface should be rounded and smooth and devoid of angular projections. The presence 95 100

of such projections seems to affect the quality adversely, to make certain notes or tones unduly prominent, and is, I believe, an important factor in producing the "blasting" 5 with which phonograph users are familiar. Whether shapes of holders such as those shown produce more favorable results because of a smoother transmission of the vibration through the stylus to the diaphragm, or 10 because of improved amplification of the vibrations in the stylus itself, is difficult to determine. The fact that a superior reproduction is obtained, however, has been conclusively demonstrated.

15 I have also found that an improvement in quality is produced by the application of this same principle to the construction of the needle holder and sound box or reproducer of a phonograph. Referring to Fig. 1 it will be 20 seen that the sound box 10 and the connection between this sound box and the tone arm 12 do not have the sharp projecting angles or 25 corners which are common in apparatus of this character, but the surfaces are rounded and smooth, changing gradually in dimensions at those points where heretofore projecting angles have been presented. Also, the 30 projecting angles have been eliminated from the needle holder 14 in which the needle 7 is mounted. Fig. 1 shows the needle operatively positioned on a record 15 mounted on the usual revolving table 16.

In order to be able to select styli suited to 35 the requirements of the selection being played, and the room or enclosure in which the selection is rendered, I prefer, even with a construction such as that shown in Fig. 1, to use styli of the forms shown, for example, in 40 Figs. 2 to 5, inclusive, in the needle holder 14 instead of mounting the needle 7 directly in this holder, as in Fig. 1. Such an arrangement, therefore, is illustrated in Fig. 1a which shows a stylus of the form illustrated 45 in Fig. 3 mounted in the holder 14.

50 It is possible, also, to make styli of the general form shown in Figs. 2 to 5 of a one-piece or integral construction, and Figs. 2a and 5a, inclusive, show at 2' to 5' one-piece constructions corresponding in general form to those 55 shown in Figs. 2 to 5. A difficulty encountered, however, in the manufacture of the styli shown in Figs. 2a to 5a is that of properly tempering the needles or points. It is usually preferable, therefore, to make the 60 needles removable, as in the construction shown in Figs. 2 to 5. This permits the use of one set of stylus bodies or needle holders with different sizes of needles and it is more economical since the bodies or holders will last almost indefinitely, the needles being replaced as soon as they become worn.

65 While I have described and illustrated typical constructions of styli embodying my invention, it will be understood that the invention may be embodied in a great variety of

other forms without departing from the spirit or scope thereof.

Having thus described my invention, what I desire to claim as new is:

1. A stylus for phonographs, comprising a relatively massive body of approximately globular form and devoid of prominent projecting angular parts, said body having a socket to receive a needle and serving to support the needle, and means for releasably securing a needle in said body. 70

2. A stylus for phonographs, comprising a relatively massive rigid body of non-metallic material, said body having smooth exterior surfaces and being devoid of prominent angular projecting parts, and a needle 75 removably secured in said body. 80

3. A stylus for phonographs, comprising a relatively massive body of non-metallic material, said body having smooth exterior surfaces and being devoid of prominent angular projecting parts, said body having a socket to receive a needle and having a reduced shank projecting from the side of said body opposite to said socket, and means for 85 releasably securing a needle in said socket. 90

4. A stylus for phonographs, comprising a needle holder consisting of a relatively massive body having smooth exterior surfaces and devoid of prominent angular projecting parts, said body being between $\frac{3}{8}$ and $\frac{1}{4}$ of an inch in diameter, and having a socket therein to receive a needle, and a shank projecting from said body and adapted to be secured in the socket of a phonograph reproducer. 95

5. In a phonograph reproducer, a needle holder comprising a relatively massive rigid body having smooth exterior surfaces and devoid of prominent angular projecting parts. 100

6. A stylus for phonographs, comprising a relatively large body having rounded external surfaces and devoid of prominent projecting angles, a shank projecting from said body at one side thereof and adapted to be secured in the socket of a phonograph reproducer, said body having a socket therein to receive a needle and support the needle in playing position with the needle projecting at the opposite side of said body from 110 said shank, and means for releasably securing a needle in said body. 115

ALFIO RAPISARDI.
